INSULATED FOOD KEEPER

David Douglas, 1332 S. 26th St.,
Manitowoc, Wis. 54220

Filed Feb. 19, 1969, Ser. No. 15,829

Term of patent 14 years

Int. Cl. D7—99

U.S. Cl. D44—1

FIG. 1 is a perspective view of an insulated food keeper showing my design;

FIG. 2 is a front elevational view;

FIG. 3 is a side elevational view;

FIG. 4 is a top plan view; and

FIG. 5 is a bottom plan view.

I claim:

The ornamental design for an insulated food keeper, substantially as shown.
